FOLDING SUPPORT FOR FOLDING TABLES

Herman Larsson, Hedemora, Sweden

Application September 25, 1933, Serial No. 690,904
In Sweden February 16, 1933

1 Claim. (Cl. 311—19)

The present invention relates to improvements in a folding table of a kind which is fixed hingedly to a wall and kept in its horizontal position by means of a support and the invention relates especially to such a folding support.

5 The inconvenience of folding tables of known construction is that the support takes up too much space if the table top is not used, that is to say if the same is in the vertical position, parallel to the wall.

10 This inconvenience is avoided with the folding table according to the present invention, as a folding support is used which is covered completely by the table top if the same is in the vertical position, and which support is kept 15 in its folded position by a special arrangement described later on. By this arrangement the folding table can be used preferably in motor-cars and the like with which care must be taken that the table does not take up too much 20 space in the inoperative position and that the table top is also kept in this position.

An embodiment of the invention is shown on the accompanying drawing:

25 Fig. 1 is a perspective view of the table in the position of use.

Fig. 2 is a front view of Fig. 1.

Fig. 3 shows the table seen from the back side if the table top is in the vertical position.

30 Figs. 4, 5, 6, 7, 8 and 9 show details in a larger scale.

The table consists in known manner of a table top 1, which is surrounded by a frame 2 and movably fixed on the wall by means of holding devices 3, so that the table top can be moved to the horizontal position in which position it is kept by means of a support, which is movably fixed with one end on the frame 2. The other end of the support is kept by a holder 5 fixed to the wall (compare Fig. 1).

40 The support itself consists of two main parts, namely an upper part which consists of two shanks 6—6 fixed on the frame 2 by means of links 7—7 and of an arm 8 fixed on one end with the two shanks 6—6 whilst the other end

45 of the same is in engagement with the holder 5 if the table top is in the horizontal position. As results from Figs. 2 and 3 the two shanks 6—6 form an angle of about 90° and the lower ends of the same and the upper end of the arm 8 are connected by a bolt 9. The lower end of the arm 8 has the form of a fork in order to avoid the disengagement of the arm 8 with the holding device 5, which is provided for this

50 reason with a projection 10 as shown in Fig. 4. By the arrangement of the above described parts a support is formed which keeps the table top in the best manner.

If the table is to be brought into the folded

position as indicated by arrow A, the arm 8 is brought out of engagement with the holding device 5 and folded in the direction of the arrow B (Fig. 1) whereby it takes a position between the shanks 6—6 as indicated in Fig. 3. In order to keep the shanks 6—6 and the arm 8 in the position on the under side of the table top, U-formed clamps 11 are provided with which the parts are brought in engagement.

5 In order to keep the table in the vertical position, that is to say on the wall, the arm 8 is provided with a spring 12 which comes in engagement with the extension 10 of the holding device. The lower holding device 5 may be so placed as to allow the extension 10 thereof to support the front edge of the frame 2 when 15 the table is folded. In such case, holders 3 should be made vertically slidable as shown by Figs. 7, 8, and 9, in which T-shaped lugs 17 on the holders 3 may be inserted in bayonet slots 20 18 in bracket 16.

As mentioned before the table top is hingedly fixed to the wall by means of holding devices 3, one of which is shown in Figs. 4 and 5. Each holding device has an arm 13, the front part 25 of which is provided with a hole 14, the cross section of which corresponds approximately to the cross section of the frame part 2 of the table top. In order to keep the frame part in its position in the hole 14, an arm 15 is provided which is pivotally fixed to the holder by 30 means of a bolt and which arm can be moved in the direction of the arrow in Fig. 6.

It is understood that the invention is not limited to the features as stated above. The 35 shanks 6—6 can be fixed on another place of the frame 2 i. e. on the side parts, and the movable connection between the shanks 6, 6 and the arm 8 can be executed also in another manner without departing from the spirit of 40 the present invention.

I claim:—

A foldable support for folding tables comprising in combination a frame, two holding devices 45 hingedly connected at one side of said frame and adapted to be attached to a wall, two stays hingedly connected at one end one near each corner of the side of said frame opposite said holding devices, said stays converging towards the other ends, a central stay hingedly connected 50 at one end to the convergent ends of said first mentioned stays, a fork on the other end of said last mentioned central stay and a support adapted to be fixed on the wall below and in a plane intermediate of said holding devices to 55 engage said fork to maintain the frame in the horizontal position.

HERMAN LARSSON.
